UNITED STATES PATENT OFFICE.

ALBERT BERNARD ROSENFIELD, OF SHANGHAI, CHINA.

DESIGN FOR A PLAYING CARD.

Application filed May 12, 1924. Serial No. 9,570. Term of patent 14 years.

To all whom it may concern:

Be it known that I, ALBERT BERNARD ROSENFIELD, a citizen of the United States, residing at Shanghai, in the Province of Kiangsu, country of China, have invented a new, original, and ornamental Design for a Playing Card, of which the following is a specification, reference being had to the accompanying drawings, forming part thereof.

The figure is a plan view of a playing card showing my new design in exact size.

I claim:

The ornamental design for a playing card, as shown.

ALBERT BERNARD ROSENFIELD.
